UNITED STATES PATENT OFFICE.

HENRY THADEOUS FRANKLIN, OF DAWMONT, WEST VIRGINIA, ASSIGNOR OF ONE-HALF TO MATT EDWARD HOOD, OF DAWMONT, WEST VIRGINIA.

COAL-LOADING MACHINE.

1,304,869.

Specification of Letters Patent. Patented May 27, 1919.

Application filed November 26, 1918. Serial No. 264,194.

To all whom it may concern:

Be it known that I, HENRY THADEOUS FRANKLIN, a citizen of the United States, resident of Dawmont, in the county of Harrison and State of West Virginia, have made 5 a certain new and useful Invention in Coal-Loading Machines; and I declare the following to be a full, clear, and exact description of the same, such as will enable others skilled in the art to which it appertains to 10 make and use the invention, reference being had to the accompanying drawings, and to letters or figures of reference marked thereon, which form a part of this specification.

15 Figure 1 is a side view of the invention with shovel retracted and lowered.

Fig. 2 is a similar view with shovel raised.

20 Fig. 3 is a similar view partly in section and broken away, showing the shovel thrust forward.

The invention has relation to coal loading 25 machines, designed to load the mined coal upon the car in the mine, having for its object to relieve the miner of much laborious work in lifting the coal and throwing it upon the mine car, and to accomplish the loading of the coal more rapidly.

30 The invention consists in the novel construction and combinations of parts, as hereinafter set forth.

In the accompanying drawings illustrating 35 the invention, the numeral 2 designates a post or standard, having at its upper and lower ends rotatable supporting engagement with the floor and roof of the mine, and fulcrumed to said post at 3 is an arm or beam 4, adapted for movement in a vertical plane, or upwardly and downwardly, through operation of a hand lever 5, the 40 latter having a flexible rope or cable connection 6 with the free end of said arm, an intermediate lever 7 being fulcrumed to said post at 8, and being operated by said hand lever to assist in raising said arm. At 45 the end portion of the upward movement of said arm, the hand lever acts through the medium of said intermediate lever alone, the cable being slack.

A shovel 9 is carried by the outer end 50 portion of the arm 4 through the medium of links 10 and 11, respectively pivoted to the arm, said links being respectively pivotally connected to the shovel at the outer or free end of the handle of the latter and 55 intermediately of the length of said handle.

The shovel is designed to be worked forwardly and backwardly as a workman would operate it in throwing coal upon the car, and to this end a hand lever 12 pivoted to the post at 3, has a rod connection 14 with the upper end of the rear link 10, and upon operation thereof in one direction or forwardly will withdraw or retract the shovel and at the same time put a coiled spring 13 under tension, said spring connecting the 60 rear end portion of the handle of the shovel with the forward end of the arm 4, and the tension of the spring being held or maintained by a pawl 15 carried by the hand lever 12 and engaging the teeth of a rack 16 65 upon said arm.

It being then desired to throw or thrust the shovel forwardly into the coal pile by a sudden movement, the pawl 15 is knocked 70 down out of engagement with the rack 16 by a blow upon the handle end thereof, the spring 13 at once acting to accomplish the 75 desired quick throw of the shovel.

The shovel being now located in the coal pile is lifted thereout by an upward movement of the arm 4 brought about by operation of the hand lever 5, the shovel carrying therewith its load of coal, and the lifting movement of arm and shovel being stopped when the shovel has arrived at a proper 80 degree of elevation to retain its load, the shovel being then substantially horizontal 85 or slightly tilted rearwardly.

The shovel being in the raised position stated, elevated above the coal pile, is given 90 a bodily movement of rotation through rotary movement of the post 2, in order that the shovel may be placed in position adapted for discharge upon the mine car, this discharge being accomplished by a second 95 working of the hand lever and operation of the spring 13 as first described for these parts.

In the quick movement or thrust of the shovel last stated it is necessary to stop the 100 shovel suddenly, in order that its load of coal may leave it properly or be properly discharged upon the mine car, and to this end the handle of the shovel where it is pivoted to the link 11 engages a slot 18 of 105 said link, and contacts with the upper beveled wall 19 of said slot, the rear link 10 at the same time being brought into alined position with relation to the shovel handle.

By this method of discharge, similar to 110

that commonly employed in manual operation, the necessity for raising the arm 4 to a height sufficient for a dumping discharge is obviated.

5 I claim:—

1. Means for loading coal, consisting of a post, an arm pivoted to said post, a shovel having a handle provided with link connection with said arm, a spring connecting the 10 arm with said handle, a hand lever having connection with the rear link to retract the shovel and put said spring under tension, releasable means for retaining said lever in position with the spring under tension, said 15 spring acting to thrust the shovel forwardly upon release of said retaining means, and means for raising the arm and the shovel.
2. Means for loading coal, consisting of a post, an arm pivoted to said post, a shovel 20 having a handle provided with link con-

nexion with said arm, a spring connecting the arm with said handle, a hand lever having connection with the rear link to retract the shovel and put said spring under tension, 25 releasable means for retaining said lever in position with the spring under tension, said spring acting to thrust the shovel forwardly upon release of said retaining means, the link connection of the shovel handle with said arm being adapted to suddenly check 30 the forward thrust of the shovel in the discharge of its load, and means for raising the arm and the shovel.

In testimony whereof I affix my signature in presence of two witnesses.

HENRY THADEOUS FRANKLIN.

Witnesses:
